CLAIM

The ornamental design for a mid-sole cleat, as shown and described.

DESCRIPTION

FIG. 1 is a perspective view of a mid-sole cleat;
FIG. 2 is a top view thereof;
FIG. 3 is a side view thereof;
FIG. 4 is a bottom view thereof;
FIG. 5 is a front view thereof; and,
FIG. 6 is a back view thereof.
FIG. 7 is a perspective view of another embodiment of a mid-sole cleat;
FIG. 8 is a top view thereof;
FIG. 9 is a side view thereof;
FIG. 10 is a bottom view thereof;
FIG. 11 is a front view thereof; and,
FIG. 12 is a back view thereof.

The dashed lines show portions of the mid-sole cleat that form no part of the claimed design.

1 Claim, 6 Drawing Sheets
